UNITED STATES PATENT OFFICE.

AUGUSTE PICTET, OF GENEVA, SWITZERLAND.

TELEPHONE INSTALLATION.

1,009,689.

Specification of Letters Patent. Patented Nov. 21, 1911.

Application filed September 9, 1911. Serial No. 648,457.

To all whom it may concern:

Be it known that I, AUGUSTE PICTET, a citizen of the Swiss Republic, and resident of Geneva, Switzerland, have invented new and useful Improvements in Telephone Installations, of which the following is a full, clear, and exact specification.

The present invention relates to an improvement in telephone installations which consists in bringing any desired advertisement to the ears of a caller through his receiver—without interfering with the operation of the system—during the time of waiting taken to complete speaking connections with the called station; this time of waiting includes: 1, the time from the taking down of the receiver at the calling station up to the response of the exchange or connection exchange station; 2, the time taken for the exchange to connect itself to another exchange in case the called station is not on the same exchange as the calling station as is often the case in large towns; 3, the time until the called station responds.

The improved arrangement constitutes a real means of advertising from which the person calling cannot escape.

In the accompanying drawings the improvement is illustrated as applied to an installation on the well known common battery system (of the Western Electric Company); the conductors and parts necessary to the invention are shown in thicker lines.

Figure 1 is a complete diagram of connections of such an improved installation; Fig. 2 is a diagram of the connections constituting the improvement alone.

Obviously the present invention can be applied to telephone installations of any system whatever.

Before the improvement is further detailed it may be well to describe a telephone installation of the known common battery system for one subscriber's station (Fig. 1). ⁴⁵ *K_v* are the usual three part jacks at the exchange through which subscribers are connected by means of the well known three part plugs; *K_a* is the inquiry jack belonging to them, *AR* a calling relay for each line, which controls the calling lamp *Al*; *TR* is a disconnecting relay with two armatures which disconnects the calling relay during the time of a conversation, and *CR* is an auxiliary relay common to the whole operator's bench operating two pilot lamps *P_l*, *P_l¹*. *ZB* is the central or common battery

which is shown in two places but of which there is actually but one; its positive pole is connected to the line wire *a* of the subscriber's station and its negative pole is connected over relay *AR* to line wire *b*. *AS* is the inquiry plug of an operator's set which is connected to a three-cored cable, between the two cores *a¹*, *b¹* of which is connected the central battery *ZB*, while the third core *c¹* of said cable contains two clearing lamps *S¹*, *S²* which are controlled by two clearing relays *SR¹*, *SR²*; and finally *H* is the so-called listening key which as may best be seen from Fig. 2 may be put into a calling position (*x*), a through speaking position (*y*) and an inquiry position (*z*). All these are known devices and shortly they operate as follows.

If the receiver is taken from the hook at ⁷⁵ the subscriber's station to which the lines *a*, *b* lead so that the circuit of battery *ZB* is closed over *a*, *b*, the current from the battery excites the relay *AR* and this through its armature closes the circuit for the calling lamp *Al* and for the auxiliary relay *CR*; the latter is actuated and closes the circuit for the two pilot lamps *P_l*, *P_l¹*. The operator now puts the inquiry plug *AS* of her speaking set into the inquiry jack *K_a* and ⁸⁵ so connects the wires *a*, *b* to the corresponding cores *a¹*, *b¹* of the inquiry cable. Since the battery *ZB* is connected between these cores, current flows from it over the clearing relay *SR¹* to the subscribers' lines. At ⁹⁰ the same time current passes from the battery, the positive pole of which is earthed, over the core *c¹* of the operator's cable and through the lamp *S¹* to the casing of *K_a*, from whence it passes through the disconnecting relay *TR* to earth. The disconnecting relay is actuated and disconnects the lines *a*, *b* which end upon its armatures from the battery *ZB* and from the calling relay *AR*. The lamp *S¹* is prevented from lighting because it is shunted by the resistance *w¹* and the attracted armature of the clearing relay *SR¹*. By movement of the listening key *H* (in Fig. 1 upward, in Fig. 2 to the right) the operator's inquiry device, not shown, which is joined to the conductors *m* is connected in. If now the desired line is free, the connecting plug *VS* is put into the multiple jack *K_v*. Current then flows from the negative pole over wire *c¹* of the plug ¹⁰⁵ cable through the lamp *S²*, plug *VS*, the jack casings and the disconnecting relay of

the second subscriber's line to earth and so disconnects its calling relay. The lamp S^2 lights up until the subscriber who is called by movement of the switch H (in Fig. 1 downward and in Fig. 2 to the left) takes down his receiver and so opens the path for the battery current over his station. Relay SR^2 then responds and its armature shunts the lamp S^2 . When the receivers are again hung up after the conclusion of the conversation, relays SR^1 and SR^2 cease to be excited. Their armatures fall back and the clearing lamps S^1 , S^2 light up.

Turning now to the actual improvement the lines a , b of each subscriber's station are connected through two wires g , h to bus bars i , j which in their turn are connected directly or through an induction coil IR with one or more microphones MR . In front of these microphones is a phonograph or other speaking machine which perpetually repeats some advertisement, for example, "Drink X's Cocoa," or repeats this in alternation with other advertisements. The auxiliary circuit g , h contains the armature e^0 of an electromagnet E having two windings e^1 , e^2 , of which the winding e^1 is connected in series with the calling lamp A^1 of the first subscriber's station, while the other winding e^2 is joined on the one hand to the positive pole of the battery ZB and on the other hand to an additional jack casing k mounted upon the inquiry jack Ka . The inquiry plug AS has an additional connecting piece k^1 corresponding to this additional jack casing k and this is connected with a fourth core d^1 of the operator's cable; when the plug AS is put in, this core d^1 connects the winding e^2 over a second armature r of the clearing relay SR^2 of the second or called subscriber's station and over an interrupter H^1 controlled by the listening key H to the negative pole of the battery ZB . The interrupter H^1 is so arranged and so controlled by said key that in the through speaking position of the key the circuit of the core d^1 is closed (see Fig. 2). As soon as the receiver is taken down at the first or calling station the corresponding calling lamp A^1 lights up as above described and at the same time the electromagnet E , the winding e^1 of which receives current, attracts its armature e^0 so that the auxiliary circuit g , h of the calling station is closed and the calling subscriber is put into connection with the induction coil IR so that he hears the advertisements spoken into the microphone or microphones MR . When the operator puts the inquiry plug AS into the appropriate inquiry jack Ka and moves the listening key H into the inquiry position so as to put herself into connection with the calling subscriber, thus extinguishing the calling lamp A^1 , the winding e^1 of the electromagnet E is also deprived of current at the same time

and armature e^0 is drawn back so that the calling subscriber is disconnected from the advertisement circuit and is only in connection with the operator. As soon as the operator puts the listening key H into the through speaking or middle position after connecting to the called subscriber, the interrupter H^1 which has hitherto been open is closed and current flows from the battery through the winding e^2 of the electromagnet E , which again attracts its armature e^0 and the advertising circuit is again closed for the calling subscriber, so that he again hears the advertisements until on the taking down of the receiver at the called subscriber's station the clearing relay SR^2 in its circuit receives current and attracts its armature r so as to interrupt the circuit of the winding e^2 of the electromagnet E and to so effect the disconnection of the advertising circuit. If the called subscriber belongs to a different exchange from the calling subscriber, the latter is put in connection with the advertising circuit while the operator of the one exchange puts herself into connection with the other through the ordinary service line and brings the listening key H into the through speaking position; and he remains thus connected until the called subscriber answers.

As may be seen the present invention requires no substantial alteration of existing installations. All that is necessary is the addition of a double wound electromagnet for each subscriber, the corresponding alteration of the inquiry jack and inquiry plug, and the use of an interrupter controlled by the listening key together with the necessary connecting wires. In no case is any modification necessary in the multiple jacks.

What I claim is:

1. In telephone installations, the combination with a subscriber's station and a connection exchange station of an auxiliary circuit, an electric and phonetic receiving and transmitting device on this auxiliary circuit for receiving and transmitting audible advertisements, an electric control device for controlling this auxiliary circuit, and means on the connection exchange station for setting this control device in operation when the subscriber's station calls up during the time elapsing before the completion of speaking connections.

2. In telephone installations, the combination with a subscriber's station and a connection exchange station of an auxiliary circuit branched from the lines of the subscriber's station, an electric and phonetic receiving and transmitting device on this auxiliary circuit for receiving and transmitting audible advertisements, an electromagnet on the connection exchange station for controlling this auxiliary circuit, and means on the connection exchange station for setting this

electromagnet in operation when the subscriber's station calls up during the time elapsing before the completion of speaking connections.

5 3. In telephone installations, the combination of a subscriber's station, a connection exchange station having a common battery, a calling relay, a calling lamp controlled by said calling relay, an inquiry jack with an 10 auxiliary casing part, an inquiry plug with an auxiliary connecting part, a multiple connecting plug system, a clearing relay and a listening key, an auxiliary circuit branched from the lines of the subscriber's station, an 15 electric and phonetic receiving and transmitting device on this auxiliary circuit for receiving and transmitting audible advertisements, an electromagnet on the connection exchange station for controlling said

auxiliary circuit, having two windings, one 20 of which is connected in series with said calling lamp, while the other is connected to said auxiliary casing part of the inquiry jack, a conductor connecting the battery with said auxiliary connecting part of the 25 inquiry plug and forming part of a circuit controlled by said clearing relay, and an interrupter in this latter circuit controlled by said listening key, substantially as and for the purpose described.

30 In witness whereof I have hereunto signed my name this 29 day of August, 1911, in the presence of two subscribing witnesses.

AUGUSTE PICTET.
